(57) **CLAIM**

The ornamental design for a children's chair with stool, as shown and described.

DESCRIPTION

FIG. 1 is a front perspective view of the chair portion of the children's chair with stool of the present invention, the chair removed for ease of illustration;

FIG. 2 is a left side elevation view of the chair portion of the children's chair with stool as shown in FIG. 1;

FIG. 3 is a front elevation view of the chair portion of the children's chair with stool as shown in FIG. 1;

FIG. 4 is a right side elevation view of the chair portion of the children's chair with stool as shown in FIG. 1;

FIG. 5 is a top plan view of the chair portion of the children's chair with stool as shown in FIG. 1;

FIG. 6 is a rear side elevation view of the chair portion of the children's chair with stool as shown in FIG. 1;

FIG. 7 is a bottom plan view of the chair portion of the children's chair with stool as shown in FIG. 1;

FIG. 8 is a front perspective view of the stool portion of the children's chair with stool of the present invention, the stool removed for ease of illustration;

FIG. 9 is a left side elevation view of the stool portion of the children's chair with stool as shown in FIG. 8;

FIG. 10 is a front elevation view of the stool portion of the children's chair with stool as shown in FIG. 8;

FIG. 11 is a right side elevation view of the stool portion of the children's chair with stool as shown in FIG. 8;

FIG. 12 is a top plan view of the stool portion of the children's chair with stool as shown in FIG. 8;

FIG. 13 is a rear side elevation view of the stool portion of the children's chair with stool as shown in FIG. 8;

FIG. 14 is a bottom plan view of the stool portion of the children's chair with stool as shown in FIG. 8; and,

FIG. 15 is a front perspective view of the children's chair with stool of the present invention, the invention being comprised of a chair element and a stool element.
